UNITED STATES PATENT OFFICE.

ANDREW J. NEUBERGER, OF ROXBURY, MASSACHUSETTS.

DESIGN FOR A HOUSEHOLD UTENSIL.

46,810.

Specification for Design.

Patented Dec. 29, 1914.

Application filed October 3, 1914. Serial No. 864,954. Term of patent 7 years.

To all whom it may concern:

Be it known that I, ANDREW J. NEUBERGER, a subject of the Emperor of Austria-Hungary, residing at Roxbury, in the county of Suffolk and State of Massachusetts, have invented a new, original, and ornamental Design for a Household Utensil, of which the following is a specification, reference being had to the accompanying drawing, forming part thereof.

The figure is a view in perspective of a household article, showing my new design.

I claim:

The ornamental design for a household utensil, as shown.

ANDREW J. NEUBERGER.
